UNITED STATES PATENT OFFICE.

ROBERT E. FRIES, OF CLEVELAND, OHIO, ASSIGNOR TO THE COLUMBIA AXLE COMPANY,
OF CLEVELAND, OHIO, A CORPORATION OF OHIO.

AXLE CONSTRUCTION.

1,283,143.

Specification of Letters Patent.

Patented Oct. 29, 1918.

Original application filed November 22, 1916, Serial No. 132,793. Divided and this application filed September 19, 1917. Serial No. 192,079.

To all whom it may concern:

Be it known that I, ROBERT E. FRIES, a citizen of the United States, and a resident of Cleveland, county of Cuyahoga, and State of Ohio, have invented a new and useful Improvement in Axle Construction, of which the following is a specification, the principle of the invention being herein explained and the best mode in which I have contemplated applying that principle, so as to distinguish it from other inventions.

The present invention relates, as indicated, to axle construction and is more particularly directed to an axle housing of improved construction and greater strength formed from a single blank or sheet of metal. By the formation of the housing from a single sheet it is necessary to make but one seam or joint which is welded and a single welded seam in a housing makes the same much stronger than two seams which are ordinarily on diametrically opposite sides and liable to open under severe strain. The preferred method of manufacture of my improved housing is here described for clearness but is claimed in a co-pending application, Serial No. 132,793, of which the present application is a division.

By the foregoing statement of the object and functions of the present invention, I do not mean that no axles are at present constructed out of a single sheet, for axles with open central portions are now in use; but these fall short of constituting a complete and unitary axle housing since the differential mechanism is there inclosed in a separate casing wholly independent of the axle proper, this casing merely being supported within the open center of the axle member.

By my new method it is possible to make a complete housing from a single blank in which the entire mechanism of the axle, including the differential, is both supported and inclosed. The present application covers subject matter originally described and claimed in my co-pending application filed November 22, 1916, Serial No. 132,793, the subject matter in question having been divided out of the original application.

The annexed drawing and the following description set forth in detail certain means and one mode of carrying out the invention, such disclosed means and mode illustrating, however, but one of the various ways in

which the principle of the invention may be used.

In said annexed drawings:—

Figure 1 is a plan view of the formed blank; Fig. 2 is a similar view of the blank after the initial bending or forming operation; Fig. 2', 2² and 2³ are sections on the planes 1—1, 2—2, and 3—3, respectively in Fig. 2, and Fig. 2⁴ is a side view of the member shown in Fig. 2 looking up; Fig. 2⁵ is a section on the line 2—2, Fig. 2 showing the blank where partially formed; Fig. 3 is a side view of the housing or blank after the third, or hole punching operation; Fig. 4 is a side view of the partially formed housing after the initial portion of the closing or final forming operation, this view also showing the notching at one side, although this may be omitted from the method, if desired; Fig. 4' is a section on the line 1—1 in Fig. 4; Fig. 5 is a similar view of the housing at the completion of the folding operation, showing the housing formed with the differential gear notches; and Figs. 5', 5² and 5³ are sections on the planes 1—1, 2—2 and 3—3 respectively in Fig. 5; Fig. 6 is a side view of the housing after the welding of the seam; Figs. 7, 8 and 9 are sections on the plane 7—7 in Fig. 3 showing the form of the central portion after the intermediate steps of edging, false-wiring and flattening, respectively; Fig. 10 is a side view of the blank as shown in Fig. 9 after the intermediate step of notching; Fig. 11 is a side view of the blank before the closing operation of Fig. 5 showing the positioning of the reinforcing tubes and baffle plates; Fig. 12 is a similar view showing the use of tubes having conical ends; Figs. 11' and 12' are sections on the planes 1—1 in Figs. 11 and 12 respectively; Fig. 13 is a side view of the closed housing (of Fig. 5) after the second notching and the trimming operation and after the welding (of Fig. 6); and Fig. 14 is a plan view of the finished housing, and Fig. 15 is a side elevation of a modified type of housing.

My improved method of manufacture comprises a series of main operations which are utilized in the production of a complete and inclosed axle housing from a single sheet and also of a number of minor or intermediate operations, which, while not essential, contribute to the production of a complete housing although they may either be omitted en-

tirely or carried out in other ways after the formation of the general housing. Thus, the major steps in my method are the punching of the blank, the bending of the same into 5 channel or, more specifically U-shape, the punching of the central hole, the closing or final forming operation and the welding. The other steps are ones which are preferably made a part of the complete method, but 10 are ones which may be varied considerably to suit different conditions and to produce particular housings for certain purposes. Such steps are the forming of a double center or inturned flange about the central hole, the 15 notching of the front and back of the central or differential portion of the housing, the placing of the reinforcing tubes of different kinds and the trimming of the rear hole after the final forming. For convenience and 20 clearness I will describe all of the above steps in their preferred order of occurrence.

The first step in my improved method of manufacture consists of the stamping or punching out, preferably from a flat sheet 25 or piece of stock, of a blank 1 of approximately the shape shown in Fig. 1. This blank will be seen to consist of a substantially circular central or intermediate portion 2 and alined oppositely extending arms 30 or strips 3. The annular central portion 2 is formed to produce in the final housing a hollow annular member which will constitute the differential housing of the finished axle when supplied with suitable cover 35 plates as is customary in such constructions, and the alined oppositely extending arms are intended, when formed as will be described hereinafter, to constitute the axle receiving tubes of the finished product. The 40 blank 1 is formed with slight projections 4 which supply sufficient stock to permit of a gradual enlargement or taper from the inner ends of the axle tubes into the central casing or differential housing, and the use 45 of such enlargements or extensions 4 is very desirable in order to produce a central hole on the joint side of the housing.

The second step consists in the bending or forming of the blank shown in Fig. 1 into 50 a channel or approximately U-shaped member 5, as shown in Fig. 2, and in the sections of Figs. 2', 2² and 2³. This change in form, or channeling may be accomplished in any desired manner, although preferably 55 carried out in a large punch press and to the extent indicated by the above mentioned sections. It will be understood that this forming or channeling of the blank may be carried out in one, two, or even more stages 60 if desired. For example; if carried out in two stages, then the blank will be formed as shown in Fig. 2⁵ in the initial stage and then formed into the section of Figs. 2', 2² and 2³ in the second stage.

65 The third step consists in punching a cen-

tral hole 6 in the blank as shown in Fig. 3, this hole being disposed preferably substantially centrally within and concentric with the central annular portion of the blank, and being formed, of course, to permit the 70 assembly of the differential mechanism within the finished central portion. At this point the blank will preferably be annealed to insure against damage to the metal during the steps to be described in the following paragraphs and under some conditions it may be desirable to anneal at several points in the process, but this may safely be left to those skilled in this art.

On the front side of the usual axle housing there is carried a heavy front cover plate or differential carrier which coöperates with the housing proper to constitute an inclosing chamber for the differential mechanism, and also usually coöperates with the housing proper to support the bearing in which the driven shaft is mounted. By reason of the weight and function of this front cover plate it is desirable that the same be very securely attached to the housing, and to 80 form a firm support for this cover plate and to afford greater length of threading for the attaching bolts I prefer to produce what may be termed a double center portion around the hole 6 which has been punched 90 in the central portion of the blank. The formation of this inturned flange or double center is preferably carried out in three distinct operations which are shown in Figs. 7, 8 and 9. The first of these operations 100 consists in what is known as "edging" the hole, and by this term is meant the turning up at right angles of a flange 7 as shown in Fig. 7. This flange is then turned or doubled inward upon itself, although it is 1 left spaced from the body portion of the blank as shown in Fig. 8, this operation being termed "false wiring," which is a term common in this art, and which means that the edge is curled inward as it would be if 1 a wire were placed around the flange and the edge of the latter then bent around the wire. The final step in this stage of the formation of the housing is the flattening of this inturned flange or double center 7 and 1 the final form of the hole is shown in Fig. 9, where the inturned flange 7 is parallel and in contact with the inner side of the metal about the hole.

It will be appreciated that since the double center or inturned flange is incorporated in the present construction for a specific purpose, this feature, and the steps required to produce the same, may be omitted whenever desired without in any way affecting 1 the process in its broader aspects and without departing from the spirit of the invention.

It is desirable in motor vehicle rear axles to make the differential portion of the axle 1

housing as small as possible in order to save material and weight and to increase the road clearance. It is necessary, however, that this portion of the housing be large enough 5 to receive the large driving gear which is driven by the pinion on the driving shaft, and in order to mount this gear it is customary to cut opposed notches at suitable points on the upper and lower flanges of the 10 front side of the housing. It will be understood that the use of these notches is in no way essential to such an axle, and is merely an expedient adapted to keep the overall size of the differential portion of the housing 15 within as small limits as possible. In order to provide such notches in the upper and lower flange of the differential portion of the housing, I punch out portions of metal which will leave notches 8 of the desired shape and in the desired position, as indicated in Fig. 10. Obviously this notching operation may be entirely omitted or 20 may be carried out at other stages of the manufacture of the housing, although preferably included for the reasons stated and inserted at the above stage in the method.

It is also usually desirable in such an axle to insert tubes 10 in the extending cylindrical portions for reinforcing these parts 25 (see Figs. 11 and 11'), and it is possible in the present method of manufacture to employ these tubes as arbors or mandrels, about which the arms of the housing are formed, and this will preferably be done. At the 30 inner ends of these tubes are usually disposed baffle plates 11 which support and reinforce the enlarged or tapered portions of the axle arms where they swell into the larger differential portion of the housing, and such baffle plates may be used in the 35 present construction. These baffle plates 11, if so used, will not operate as mandrels, and will not obviate the necessity for using especially constructed dies for the purpose of 40 securing the proper form and taper at this point in the housing, although these dies may be constructed to fit about the ends of the tubes, in which position they will serve as arbors to form the arms 3. The baffle 45 plates may be inserted later, and then welded into position in the usual manner. If desired, other tubes 12 with flared or conical ends 13 (see Figs. 12 and 12'), may be used 50 instead of the tubes 10 and baffle plates 11, and in this case the conical ends 13 of the tubes will serve to produce the desired section in the finished housing at this point, and will eliminate the subsequent welding 55 since the fit will be tight enough to prevent 60 the leakage of oil between the tube and axle arm, although it will be desirable to spot-weld the tubes to the arms at the inner ends.

The housing at this stage in the manufacture is still in U-shape section, but has been 65 punched, notched, the edge of the front face

of the differential portion turned inward upon itself to form a double center, and the reinforcing tubes positioned. The next step consists in the bending or shaping of this U-shape section into a member of substantially circular cross-section at its ends, and of rectangular cross-section at the central or differential portion. This closing of the U-shape section is preferably carried out in two steps, although the closing may be completed in a single operation if desired. If carried out in two steps, the first will be the starting of the closing or the bending inward of the parallel arms 9 of the U to an extent of about 30 degrees as shown in Fig. 4'. 70 The extent to which these arms are initially bent inward is shown in Figs. 4 and 4', and the initial bend given to the arms is preferably about thirty degrees from their original position. The finish of the closing operation (see Fig. 5), consists in the folding or further bending of the now inclined ends of the U into cylindrical shape, and this involves, of course, the folding around of the central portion of the U which is accomplished preferably by placing sectional forms or dies 14 within the U which will constitute a mold about which the arms of the blank can be formed. It has been stated that the above shaping of the section may be 85 completed in a single step although it is thought safer to carry it out in the successive operations specified, since the metal of the blank is less liable to malformation and breakage and the dies are simpler in construction. 90

In case the hole 6' formed in the joint or rear side of the housing is not of the right dimension (see Fig. 5), it is necessary, or at least desirable, to punch through it to trim 105 the edges to the desired size and at the same time notches 8' can be formed corresponding in position to the notches 8 on the opposite side of the housing. These two steps can be carried out simultaneously, thus producing the housing of Fig. 6. 110

The joining of the abutting edges of the formed sheet may be accomplished in various ways, the most usual and preferred method being by oxy-acetylene welding although other welding methods may be employed if desired. 115

It will of course be obvious that most of the foregoing steps in the manufacture of axle housings, according to my improved 120 method, can best be carried out with suitable punches and dies, but since the design and construction of these necessary implements can be accomplished by any one skilled in this art, I have considered it unnecessary to 125 show in detail, or to describe the form of these articles. It is also thought to be unnecessary to show apparatus for using these punches and dies, since all of the punching steps will be carried out in suitable presses 130

which are in common use in the manufacture of axle housings and other articles out of sheet metal.

In Fig. 15 I have shown an axle housing 5 of a type sometimes used in which the central portion is made up separately and then riveted to the tubes which form the arms. It will be clear that such a housing can also be made up by my new method, that is, the 10 central portion can be made up from a single sheet by the steps I have outlined. In this construction, the alined arms on the blank, (which in my previously described forms 15 constitute the axle arms) will be shortened to relatively slight extensions from the main circular portion of the blank.

The product which is secured by the present method is not only considerably stronger than an axle housing made of two separate 20 joined blanks or sections, but it is also very much cheaper to manufacture. Several operations are omitted in the present method which are essential in the other methods of manufacture, and the present axle housing 25 requires less than one half the amount of welding necessary on the usual axle.

It will be seen that my axle housing is complete, being adapted, when fitted with the usual cover plates, to not only support, 30 but also wholly inclose the driving axles and differential mechanism without the use of any additional or separate casing for any part of the operating mechanism.

Other modes of applying the principle of 35 my invention may be employed instead of the one explained, change being made as regards the mechanism herein disclosed, provided the means stated by any of the following claims or the equivalent of such stated 40 means be employed.

I therefore particularly point out and distinctly claim as my invention:—

1. As a new article of manufacture; an axle housing comprising an open annular 45 central portion constituting a differential casing, and tubes extending oppositely therefrom, said tubes and casing being integral with each other and having a single welded seam.

2. As a new article of manufacture, an 50 axle housing comprising an open annular central portion constituting a differential casing, and tubes extending oppositely therefrom, said tubes and casing being integral with each other and having a single 55 welded seam therealong on one side of said housing.

3. As a new article of manufacture, an axle housing comprising an open annular central portion constituting a differential 60 casing, tubes extending oppositely therefrom, said tubes and casing being integral with each other and having a single welded seam, and reinforcing tubes mounted in said first named tubes, said reinforcing tubes being 65 formed at their inner ends to contact snugly against said first named tubes.

4. As a new article of manufacture, an axle housing comprising an open annular central portion constituting a differential 70 casing, the front and rear faces of said central portion being provided with annular alined openings, the edge of one of said openings being turned inward to provide a flange of double thickness, and tubes formed 75 integral with such central portion and extending oppositely therefrom, and said tubes and casing having a single longitudinally welded seam.

5. As a new article of manufacture, an 80 axle housing comprising an open central portion constituting a differential casing and tubes extending oppositely therefrom, said tubes and casing being rigid with each 85 other and having a single longitudinally extending seam.

6. As a new article of manufacture, an axle housing comprising an open central portion constituting a differential casing and tubes extending oppositely therefrom, 90 said tubes and casing being integral with each other and having a single longitudinally extending welded seam on one lateral face of said housing.

Signed by me, this 14th day of September, 95 1917.

ROBERT E. FRIES.
